UNITED STATES PATENT OFFICE.

THOMAS E. MURRAY, OF NEW YORK, N. Y.

CRUDE-OIL STILL.

1,273,523.

Specification of Letters Patent. Patented July 23, 1918.

Application filed December 14, 1916. Serial No. 136,863.

To all whom it may concern:

Be it known that I, THOMAS E. MURRAY, a citizen of the United States, residing at New York, in the county of New York and 5 State of New York, have invented a certain new and useful Improvement in Crude-Oil Stills, of which the following is a specification.

The invention relates to crude oil stills, 10 and more particularly to the removal of non-volatile residue from said stills.

Heretofore the process of refining crude petroleum has been to convey it by suitable piping to a horizontal cylindrical tank, set 15 in masonry containing also a grate, fire-box, flues, etc. The various products of distillation are given off in turn as the temperature rises, and the non-volatile residue is deposited on the bottom of the tank. In order to 20 remove this residue after the distillation is complete, the fire is drawn, and after the still and masonry are cooled sufficiently to permit men to enter the tank through manholes in its ends, said residue is manually 25 shoveled out—a proceeding which wastes the time necessary for the cooling of the still and renders the labor necessary for the removal of the residue both onerous and disagreeable.

30 My invention consists in disposing within the still which is provided at one end with a delivery opening suitable for the extraction of the solid residue or coke, means for continuously comminuting and stirring said 35 solid residue or coke, and for moving the mass continuously to said delivery opening and in a direction longitudinal to said still.

In the accompanying drawings—

Figure 1 is an elevation of my crude oil 40 still, one end being in section. Fig. 2 is an enlarged cross section of the still, and Fig. 3 is a longitudinal section of the end of said still.

Similar letters of reference indicate like 45 parts.

A is a horizontal cylindrical still supported on the masonry walls B, between which are the fire grates C. D is the crude oil supply pipe, and E is the pipe leading from 50 still to condenser.

An eccentrically placed horizontal shaft F is journaled in the heads G of the still, and is rotated by any suitable means. As here shown, there is a pinion H on said shaft,

actuated by a worm I on the shaft of an 55 electric motor J.

On the shaft F are radial arms K which are preferably set alternately at right angles. On the end of each arm is pivoted a hub L which on one side of the pivot carries a 60 scraper blade M, set at an angle to the plane of its carrying arm, and on the other side, a lever N which is connected by a helical spring O to a lug on the side of said carrying arm K.

65 In one head G at the bottom of the still is an opening P which communicates with a receptacle Q, provided with a door R on its outer side.

The operation is as follows: 70

The still being filled with crude oil and fire started on the grates C, the various products of distillation are given off as the temperature rises. The non-volatile residue meanwhile descends to the bottom of the 75 still, and there accumulates. When the distillation is finished, the fires are banked and the shaft F is set in rotation, thus causing the scraper blades M to engage the deposit, and remove the same from the still wall, 80 and the said arms to comminute and stir said deposit, so that the said blades by reason of their angular inclination, convey said deposit in a direction lengthwise the still and into the receptacle Q. By reason of the 85 springs O, the pivoted scraper blades M are rendered yielding, so that the shock of their impact with the deposit is reduced and their breakage prevented. After the deposit or a sufficient quantity thereof has accumulated 90 in the receptacle, the door R is opened and said deposit manually removed.

I claim:

1. A horizontal cylindrical oil still having a delivery opening, a longitudinal rotary shaft in said still, radial arms on said shaft, and angularly placed scraping blades on the ends of said arms; whereby upon the rotation of said shaft solid material on the bottom of said still engaged by said blades 95 is moved lengthwise the still to said delivery opening.

2. A horizontal cylindrical oil still, heads therefor, one of said heads having a delivery opening, a longitudinal rotary shaft eccentrically disposed in said still and journaled in said heads, radial arms on said shaft, hubs pivoted at the ends of said arms, 100

angularly placed scraping blades carried by said hubs, levers carried by said hubs, and helical springs connecting said levers to said arms; whereby upon the rotation of said shaft, solid material on the bottom of said still engaged by said blades is moved lengthwise the still to said delivery opening.

In testimony whereof I have affixed my signature in presence of two witnesses.

THOMAS E. MURRAY.

Witnesses:

GERTRUDE T. PORTER,
MAY T. McGARRY.
